UNITED STATES PATENT OFFICE

2,634,408

ELECTRIC HORN

Richard C. Nielsen and Peter Nielsen, Omaha, Nebr., assignors, by direct and mesne assignments, of one-half to Jubilee Manufacturing Company, Omaha, Nebr., a corporation of Nebraska, and one-half to E. A. Laboratories, Inc., Brooklyn, N. Y., a corporation of New York

Application January 14, 1949, Serial No. 71,013

16 Claims. (Cl. 340—388)

1

This invention relates to improvements in electrical warning signals.

The primary object of this invention is the provision of an electric sounding signal of the vibrating diaphragm type wherein means is provided to change the stroke of the signal diaphragm during sounding of the signal for the purpose of varying the sound pitch and volume.

A further object of this invention is the provision of an improved electric horn having a built in circuit maker and breaker which is normally open: means being provided as a part of the horn structure to close the circuit maker and breaker, and to vary the sound of the horn during the operation thereof.

A further object of this invention is the provision of an improved electromagnetic vibrating horn capable of producing an undistorted tone which may be varied as to pitch and volume during the sounding thereof.

Other objects and advantages of this invention will be apparent during the course of the following detailed description.

In the accompanying drawings, forming a part of this specification, and wherein similar reference characters designate corresponding parts throughout the several views,

Figure 1 is a side elevation of the improved horn.

Figure 2 is a plan view of the horn.

Figure 3 is a vertical cross sectional view taken substantially on the line 3—3 of Figure 2.

Figure 4 is a fragmentary cross sectional view taken through the upper part of the horn.

Figure 5 is an inside plan view of the part of the horn carrying the electromagnet and circuit maker and breaker assemblage.

Figure 6 is a fragmentary cross sectional view of the upper part of the horn, taken substantially on the dot and dash line 6—6 of Figure 2 and showing associated features of the operating linkage and diaphragm assemblage, including the electromagnet armature.

Figure 7 is a fragmentary sectional view showing other details of the horn structure.

Figure 8 is a wiring diagram of the circuit maker and breaker assemblage of the horn structure showing the contacts open, the control linkage being shown in dot and dash lines.

Figure 9 is a diagrammatic view of the parts shown in Figure 8, but with the control linkage in position to close the circuit maker and breaker contacts for the purpose of setting the signal in operation.

Figure 10 is another diagrammatic view of the parts shown in Figures 8 and 9, but with the diaphragm in position which it will assume upon

2

attraction of its armature by the electromagnet for the purpose of breaking the magnetic coil circuit.

In the drawings, wherein for the purpose of illustration is shown only a preferred embodiment of the invention, the letter A may generally designate the electric warning signal or horn. It includes a casing or frame structure B; electromagnet C; diaphragm and armature assemblage D; circuit maker and breaker assemblage E, and control linkage F.

The casing structure B includes the portions 10 and 11 which are respectively annularly flanged at 12 and 13 for receiving between the outer peripheral portion of the diaphragm 15 constituting part of the assemblage D. The flanges 12 and 13 may be connected by rivets 16, or detachably connected by bolts if so desired. The casing portion 11 includes the bell mouth 18. The casing portion 10 houses and supports the electromagnet C; the circuit maker and breaker assemblage E, and the control linkage F. To that end it includes the outer cup-shaped portion 20 defining a compartment 21 therein to receive the electromagnet C. The portion 20 is provided with an annular flange 23 paralleling the top wall 24 of the casing portion 20, and an annular wall portion 25 connects the flanges 12 and 23.

The electromagnet structure C includes the U-shaped steel pole piece 30, core 31 and coil 32. These parts are mounted detachably by nut and bolt means 33 upon the top wall 24 of the casing portion 10, with the core 31 extending from the coil within the compartment 21 of the casing portion 10, as shown in the drawings, between the arms of the pole piece 30.

One end of the coil 32 is connected to a live terminal 40 mounted on the casing, as shown in Figure 4; the terminal 40 being insulated at 41 (see Figure 4) from the casing structure B, which of course is grounded in a circuit, usually the chassis frame of the automotive vehicle to which the signal is attached. The other end 45 of the coil 32 is connected in circuit to a terminal screw 44, shown in Figures 5 and 6 which is in circuit with a leaf spring type contact arm 45 forming part of the circuit maker and breaker assemblage E. The leaf spring arm 45 is mounted in insulated relation upon casing 10 by means of the terminal screw 44 and another screw 46 mounted upon the casing wall 23. The spring arm structure 45 extends transversely across the compartment in the casing portion 10, as shown in Figures 5 and 6, and is adapted to carry both

coil and resistor contacts 70 and 105 to be subsequently described.

The diaphragm and armature assemblage D preferably comprises the flexible sheet metal diaphragm 45 of sufficient springiness to inherently assume a predetermined position; the peripheral margins thereof being clamped between the flanges of the casing portion 10 and 11, as indicated in the various views of the drawings. As will be noted from Figure 3, the armature is attached centrally to the diaphragm 45 and includes the rectangular-shaped portion 52 clamped by means of a detachable bolt assemblage 51, of head portion 50 of which faces the core. The armature portion 52 is provided with a pair of outstanding right angled studs or prongs 53 at diametrically opposed sides of the electromagnet core 31 for cooperation with the spring arm portions 57 and 58 of a leaf spring yoke 60. The latter is secured at 61 to the wall portion 23 of the casing 10 within the electromagnet compartment of the casing structure 10. The yoke has arms 57 and 58 in straddling relation with the electromagnet core 31, as will be noted from the various views of the drawings, and particularly Figure 5, and in which view in dot and dash lines designate the relative positions of the armature studs or prongs 53.

The leaf spring contact arm 45 intermediate its ends is provided with the coil contact point 70 located in a plane intersecting the central axis of the leaf spring yoke 60; the latter at the juncture of the spring arms 57 and 58 supporting a complementary contact point 71; the relation of these parts being best illustrated in Figures 6 and 7.

The control linkage F is provided for the purpose of closing a normally open circuit through the electromagnet coil structure. To that end it includes a connecting rod or plunger 80 reciprocably supported upon the end wall 24 of the casing structure 10 in right angled relation therewith; its inner end being detachably and securely clamped in insulated relation upon the leaf spring arm 45, intermediate the ends of the latter, as shown in Figure 6 of the drawings. A compression spring 85 is situated between the leaf spring 45 and the under side of the wall 24 of the casing normally urges the leaf spring 45 into the position shown in Figure 6. An operating lever 88 is pivoted at 89 upon a bracket structure 90 secured upon the outer surface of the casing wall 24; a cam end thereof extending beneath the end washer 91 upon the connecting rod or plunger 80. The spring 85 is under compression in the relation of parts shown in Figure 6 with the cam end of the lower arm portion of the bell crank operating lever 88 clamped between the top surface of the wall 24 and the under surface of the washer 91 to hold the circuit contacts open.

A resistor element 100 is located upon the inside surface of the wall 23; one end of it being secured upon the casing structure by rivet 101. Its opposite end is secured to a terminal bolt 105 mounted in insulated relation upon the casing wall 23 as shown in Figure 3. This terminal 105 provides a contact point for complementary cooperation with a contact point 106 secured upon the extreme outer end of the leaf spring type contact arm 45.

The metal casing structure B of the horn or signal will be grounded in circuit with a suitable source of direct current, such as a battery 110. While the wiring in diagrams shown in Figures 75

8, 9 and 10 is not shown as grounded for the battery and the casing of the horn, the circuit may be grounded as to both the casing and battery at 111. The hot side of the battery is connected to the live terminal 40 of the casing structure, this being indicated by the line 112 in Figures 8, 9 and 10 of the drawings. In the wiring diagrams the reference characters applied to the various parts of the warning signal are the same as those above designated. With the control linkage in the off position shown in Figure 8, the coil contact points 70 and 71 are spaced as are also the resistor contact points 105 and 106. Moving the bell crank lever 88 against the resistance of the spring 85 will pull the arm 45 to engage the coil contacts 70 and 71. The coil 32 becomes energized and attracts the armature 52. The studs 53 which engage the leaf spring yoke 60 upon which the coil contact point 71 is mounted moves the yoke away from the contact point supporting arm 45. This separates the contact points 70 and 71 and the circuit is broken through the coil. This position is shown in Figure 10 of the drawings. The diaphragm 45 now being under spring tension will move, as soon as the circuit is broken, from the position shown in Figure 10 to normal position. The prongs 53 move therewith and permit the spring yoke arm 60 to move, due to its inherent springiness, so that its terminal point 71 will again engage the terminal point 70 for again closing the circuit through the coil, and thus the cycle continues; the diaphragm vibrating and setting an air column in action.

The resistor circuit is provided for the protection of the coil contact points 70 and 71, in order to reduce flash as the contact points 70 and 71 open and close. The coil contact points 70 and 71 are set to close just slightly ahead of the resistor contact points 105 and 106. When the coil contacts 70 and 71 open at the limit of instroke of the armature, as shown in Figure 10, it is to be noted that the resistor contacts 105 and 106 are engaged. Thus a current is flowing through the magnet coil even though the coil contacts 70 and 71 are separated. The force of this current, however, is small, since it is controlled by the resistor unit 100, and this does not interfere with diaphragm action.

Referring to improved features in operation of the warning signal, it is to be noted that all switch contact points within the casing structure are normally open. This is in contradistinction to other horn structures whose breaker points are normally closed. It is not necessary to provide a push button control for the horn circuit; conventional push button structure for ordinary horns normally keeping the electric circuit open remote from the horn structure. The present invention has the advantage of economy and simplicity, because it eliminates separate push button electrical control elements with all of their attendant wires, terminals, relay structure, etc.

In the improved warning signal the control linkage enables the frequency vibration of the diaphragm assemblage to be changed during sounding of the horn. This is accomplished by changing the relative position of the breaker points 70 and 71 through the control linkage. Holding the control linkage in predetermined position during sounding of the horn spaces the contact points of the circuit for the coil in a predetermined relation so that there will be a constant stroke of the vibrating diaphragm and the

volume and pitch of tone of the horn will remain constant. However, if the control linkage is now moved so as to farther space the contact point 70 of the spring arm structure 45 from the plane of the diaphragm, such will also move the contact point 71 farther away from the diaphragm and make it necessary for the diaphragm to travel a greater distance in order that the studs 53 can lift the spring blade 60 and disengage the breaker points 70 and 71 and open the circuit. This length of travel or stroke of the diaphragm depends on the position in which the operator places the control linkage. Since the lever of the control linkage can be moved either way while the horn is blowing, the sound produced can be varied during blowing of the horn to suit the operator's pleasure. It is obvious that the volume and pitch depend upon the length of stroke of the diaphragm, and such variation produces an undistorted tone which is pleasant, distinctive, etc.

It is important to note that the means for moving the coil terminals, etc. insures a pure undistorted tone, because the breaker points open and close in a plane intersecting the center of the diaphragm; the electromagnet thus being enabled to pull the diaphragm assemblage straight to the magnet and to permit its release in a plane normal to the axis of the coil. There is no buckle and weaving during vibration of the diaphragm and this tends to produce a clear and undistorted tone.

At the start the operating movement of the control linkage will vibrate the diaphragm to produce a tone which is low in pitch and volume, but as the control linkage plunger moves to lengthen the stroke of the diaphragm, the sound volume increases with a higher pitch.

Various changes in the shape, size and arrangement of parts may be made to the form of invention herein shown and described without departing from the spirit of the invention or the scope of the following claims.

We claim:

1. In an electric sounding signal the combination of a casing, a sound producing vibrator carried by the casing, an electromagnet carried by the casing having a coil, an armature for the magnet carried by said vibrator, an electric circuit for the electromagnet including a circuit maker and breaker carried by the casing, and means for directing a minor current through the electromagnet coil just prior to and during opening of the circuit maker and breaker.

2. In an electric horn the combination of a casing, a vibrating diaphragm carried by the casing structure, an electromagnet including a coil carried by the casing, an armature for the electromagnet carried by said diaphragm, a circuit maker and breaker carried by the casing including a pair of spring arms having normally disengaged contact points thereon, a circuit connected with said spring arm contact points for said coil, means for moving said contact points into closing relation, means operated by the diaphragm and armature for moving one of the spring arms to a circuit opening position immediately after closing of the circuit by said contacts, and means for selectively varying the position of the spring arm upon which the other contact point is mounted so as to vary the effective opening and closing relation of the circuit by said contact points with respect to the normal position of the diaphragm in order to control the frequency stroke of said diaphragm.

3. In an electric horn construction the combination of a casing, a vibrating diaphragm carried by the casing having an armature connected therewith, an electromagnet carried by the casing including a coil in operating relation with respect to said armature, a circuit for the coil, a circuit maker and breaker including individual yieldable members mounted upon the casing having individual normally disengaged contact points thereon for said circuit, means carried by the casing for closing said contact points, said last mentioned means operating to move said individual members to vary the position of said contact points with respect to the rest position of said diaphragm in a line normal to the plane of the diaphragm, and means associated with said diaphragm and armature for moving one of said members and its contact point away from the contact point of the other member to disengage said points and open the circuit upon extended movement of the armature as an incident of attraction by said electromagnet.

4. In an electric horn structure the combination of a casing, a diaphragm mounted in the casing structure, an electromagnet carried by the casing, an armature for the electromagnet carried by the diaphragm, a resilient circuit making and breaking arm carried by the casing, a second resilient circuit making and breaking arm carried by the casing, a circuit for said coil, normally spaced contact points for the circuit carried by said arms, operating means to engage the points and close the circuit, and means operated by the armature and diaphragm for moving one of said arms to necessitate disengagement of the contact points at extended positioning of the armature and diaphragm as an incident of attraction by said electromagnet.

5. In an electric horn structure the combination of a casing, a diaphragm for the casing structure, an electromagnet carried by the casing, an armature for the electromagnet carried by the diaphragm, a resilient circuit making and breaking arm carried by the casing, a second resilient circuit making and breaking arm carried by the casing, a circuit for said coil, normally spaced contact points for the circuit carried by said arms, operating means to engage the points and close the circuit, means operated by movement of the armature and diaphragm for moving one of said arms to disengage the contact points at extended positioning of the armature and diaphragm as an incident of attraction by said electromagnet, and means for moving said arms and varying the position of said contacts toward and away from the plane of operation of said diaphragm.

6. In an electric horn construction the combination of a casing, a vibrating diaphragm carried by the casing structure, an electromagnet carried by the casing including a coil, an armature for the electromagnet carried by said diaphragm, a resilient circuit making and breaking arm carried by the casing inherently assuming a predetermined position and having a contact point thereon, means for moving said arm to change the relative position of the contact point thereof within said casing in a line normal to the operating plane of the diaphragm, a second resilient arm carried by the casing inherently assuming a predetermined position and having a contact point connected therewith in normal disengaged relation with respect to the contact point of the first mentioned contact arm, a coil circuit for said contact points, said second con-

tact arm bearing such a relation to the first mentioned contact arm that it will also be moved by and with controlled movement of the first mentioned contact arm, and means operated by movement of the diaphragm and its armature for moving the second arm and its contact point to break a circuit immediately after energization of the electromagnet.

7. In an electric sounding signal the combination of a frame, an electromagnetic assembly upon said frame, a diaphragm mounted upon said frame having an armature connected therewith for said electromagnetic assembly, a spring arm mounted upon said frame inherently assuming a predetermined position and having an electric contact mounted thereon and movable therewith, said contacts providing a normally opened circuit maker and breaker, a circuit for said electromagnet having said contacts operatively connected therein, operating means mounted upon the frame and connected with the first of said spring arms to move the same and cause engagement of said contacts and closing of the circuit thru the electromagnet, and means mounted upon the diaphragm and movable therewith to engage the second spring arm when the diaphragm is in extended position immediately after closing of the circuit to cause movement of said second arm and disengagement of said contacts and resultant opening of the circuit.

8. In an electric sounding signal the combination of a frame, an electromagnetic assembly upon said frame, a diaphragm mounted upon said frame having an armature connected therewith for said electromagnetic assembly, a spring arm mounted upon said frame inherently assuming a predetermined position and having an electric contact mounted thereon and movable therewith, a second spring arm mounted upon said frame inherently assuming a predetermined position and having an electric contact mounted thereon and movable therewith, said contacts providing a normally opened circuit maker and breaker, a circuit for said electromagnet having said contacts disposed therein, operating means mounted upon the frame and connected with the first of said spring arms to move the same and cause engagement of said contacts and closing of a circuit thru the electromagnet, means mounted upon the diaphragm and movable therewith to engage the second spring arm when the diaphragm is in extended position to cause movement of said second arm and disengagement of said contacts and opening of the circuit, said operating means having a controlled range of movement to enable the engaged contacts to be selectively moved towards and away from the normal rest position of the diaphragm during vibration of the diaphragm whereby said diaphragm may be required to travel predetermined varied distances in order to effect disengagement of said contacts and thereby selectively controlling the length of travel of the vibrating diaphragm and the sound pitch caused thereby.

9. In an electromagnetic horn, a frame, an electromagnet mounted upon said frame, a diaphragm mounted upon said frame for said electromagnet, a circuit for said electromagnet including a circuit maker and breaker, control means for operating said circuit maker and breaker, and means operated by the control

means to vary the sound effective pitch of said diaphragm simultaneously with circuit closing operation of said circuit maker and breaker.

10. In an electromagnetic horn, a frame, an electromagnet mounted upon said frame, a diaphragm mounted upon said frame for said electromagnet, a spring arm mounted upon said frame having a contact thereon, a second spring arm mounted upon said frame having a contact thereon in circuit making and breaking relation with respect to the contact of the first mentioned spring arm, operating means mounted upon said frame, said arms being so related in their normal position that their contacts are out of relative engagement, means normally maintaining the operating means in such position that the contacts will be out of relative engagement, a circuit having said contacts therein and having the electromagnet operatively connected therein, said operating means having connection with one of said spring arms to enable it to be moved and thereby to engage said contacts for closing said circuit and flexing the second spring arm for relatively changing the position of both of said contacts with respect to the normal plane of operation of the diaphragm, and means carried by the diaphragm for engaging the spring arm free of direct connection with the control means for causing it to move at extended positioning of the diaphragm for disengaging said contacts.

11. An electrically actuated horn having an intermittently energizable solenoid attracting a diaphragm carrying armature including in combination a reciprocable movable strip electrically connected to one terminal of said solenoid, a first contact engageable with said reciprocable strip to energize said solenoid, a member supporting said first contact mounted between said solenoid and armature so as to be vibrated by said armature and vary the position of engagement between said first contact and said reciprocable strip, a second contact engageable with said reciprocable strip to energize said solenoid at a more extreme position of reciprocation of said strip than said engagement between said first contact and said strip, a resistance connected between said first and said second contacts so that said solenoid is energized by engagement between said second contact and said reciprocable strip through said resistance and means for reciprocating said reciprocable strip.

12. In a horn having an intermittently energizable solenoid attracting a diaphragm carrying armature and a spring flexed by said armature upon attraction by said solenoid, the combination of a first contact on said spring, a movable arm disposed adjacent and transverse to said spring and electrically connected to one terminal of said solenoid, one end of said arm immovable, one end of said arm movable in a direction toward and away from said spring, a reciprocable member cooperable and movable with the movable end of said movable arm, mechanical means cooperable with said reciprocable member to variably operate said member in the direction of the movement of said arm, a second contact on said arm out of contact with said first contact in the de-energized state of said solenoid and engageable with said first contact to energize said solenoid, said reciprocation of said movable arm being variable to vary the position of engagement between said first and second contacts along the direction of the movement of said movable arm whereby actuation of said mechanical means causes reciprocation of

said reciprocable member and said movable arm to bring about a variation in the engagement between said first and second contacts and the flexure of said spring by said armature with a consequent variation in the sound produced by 5 said diaphragm.

13. In a horn having an intermittently energizable solenoid attracting a diaphragm carrying armature and a member engaged by said armature upon attraction by said solenoid the combination of a first contact on said member 10 electrically connected in the solenoid energization circuit, a first reciprocable means adjacent said member electrically connected in said solenoid energization circuit and movable in a direction toward and away from said member, a second means variably operable in the direction of reciprocation of said first means, said second means being cooperable and movable with said first reciprocable means, a second contact attached to said first reciprocable means and out of contact with said first contact in the de-energized state of said solenoid, said first reciprocable means and said second contact being movable to engage said second contact with said first contact to energize said solenoid, said reciprocation of said reciprocable means being variable to vary the position of engagement between said first and second contacts along the direction of the movement of said first reciprocable means whereby actuation of said second means causes reciprocation of said first reciprocable means to bring about a variation in the engagement between said first and second contacts and the movement of said member by said armature with a consequent variation in the sound produced by said diaphragm.

14. In a horn having an intermittently energizable solenoid attracting a diaphragm carrying armature the combination of a spring flexed by said armature upon attraction by said solenoid, a first contact on said spring movable therewith and connected in the solenoid energization circuit, a reciprocable arm independent of and disposed adjacent to said spring and electrically connected to one terminal of said solenoid, one end of said reciprocable arm immovable, the other end of said reciprocable arm being freely movable in a direction toward and away from said spring, reciprocable means cooperable with said free end of said reciprocable arm to variably reciprocate said reciprocable arm toward and away from said spring, a second contact on said reciprocable arm out of engagement with said first contact in the de-energized state of said solenoid and engageable with said first contact to energize said solenoid, said operation of said reciprocable means being variable to vary the position of engagement between said first and second contacts along the direction of the reciprocation of said reciprocable arm whereby actuation of said reciprocable means causes reciprocation of said reciprocable arm to bring about a variation in the engagement between said first and second contacts and the flexure of said spring by said armature with a consequent variation in the sound produced by said diaphragm.

15. In a horn having an intermittently energizable solenoid attracting a diaphragm carrying armature the combination of a spring interposed between said armature and solenoid, a free end of said interposed spring extending transversely halfway across said armature and anchored at the opposite end so as to be flexed by movement of said armature toward said solenoid, a first contact positioned on said spring substantially equidistant between said anchored end and said free end and electrically connected to one terminal of said solenoid, a movable arm disposed adjacent to said spring and electrically connected to one terminal of said solenoid, a fixed end of said movable arm, a freely movable end of said movable arm reciprocable in a direction toward and away from said spring, a reciprocable member cooperable and movable with the movable end of said movable arm, means cooperable with said reciprocable member to variably operate said member in the direction of the reciprocation of said movable arm, a second contact on said arm out of contact with said first contact in the de-energized state of said solenoid and engageable with said first contact to energize said solenoid, said reciprocation of said movable arm being variable to vary the position of engagement between said first and second contacts along the direction of the reciprocation of said movable arm whereby actuation of said means causes reciprocation of said reciprocable member and said movable arm to bring about a variation in the engagement between said first and second contacts and the flexure of said spring by said armature with a consequent variation in the sound produced by said diaphragm.

16. In an electromagnetic horn the combination of a frame, an electromagnet mounted upon said frame including a coil, a diaphragm mounted upon said frame in position for attraction by said electromagnet, a normally open circuit maker and breaker mounted upon said frame for closing of a circuit through the coil of said electromagnet, means carried by the diaphragm for opening the circuit maker and breaker after circuit closing during vibration of the diaphragm, and operating means for closing the circuit maker and breaker for energizing the electromagnet including means to vary the distance of circuit breaking operating of said circuit maker and breaker with respect to the diaphragm to vary the sound effective pitch of the diaphragm during horn operation.
